(57) **CLAIM**

The ornamental design for a heat sink clip, as shown and described.

DESCRIPTION

FIG. 1 is a front perspective view of a heat sink clip showing our new design;

FIG. 2 is a front view of the heat sink clip shown in FIG. 1;

FIG. 3 is a back view of FIG. 1;

FIG. 4 is a left side view of FIG. 1;

FIG. 5 is a right side view of FIG. 1;

FIG. 6 is a top plan view of FIG. 1;

FIG. 7 is a bottom plan view of FIG. 1;

FIG. 8 is a perspective view of the heat sink clip, showing environmental mounting exploded around the clip; and,

FIG. 9 is a perspective view of the heat sink clip, wherein the clip is shown assembled within the environmental mounting. The broken lines illustrate environment and form no part of the claimed design.
